the business, manufacturing company of the same place

Littleton, Mass. 01460. Tel. Gang 6-1168

Design is a Carpet Pattern

The set is intended to be used in landscape making part of the business

Business of design

It is known that Olema J. Myrick & Son, Inc.
the County of Middlesex and State of Massachusetts have originated
and designed a new pattern for carpeting fabrics of which the following
is a full, clear and exact description of the same being had to the end
company designs, making part of the business

A carpet with a black ground

Ridge roll over lapping

Carpet Casuarina palm leaves

It is a regular pattern of palm leaves

and each palm leaves are 12 inches in diameter

and each each fourth of palm

leaves are straight

The colors employed for the different parts of the design may

be varied to suit the taste and will be determined by the

designer

It is claimed as an invention and design, heretofore by letter patent

of the Design or other, or to get another patent or to prevent further

utilization
